IGNITION HARNESS

Jakob R. Frei, Sidney, N. Y., assignor to Bendix Aviation Corporation, New York, N. Y., a corporation of Delaware

Application November 20, 1944, Serial No. 564,325

5 Claims. (Cl. 174—91)

1

This invention relates to ignition apparatus and more particularly to radio shielding harnesses, or the like, and parts thereof adapted for use in shielding the conductors of an ignition system for an internal combustion engine.

It has been common and almost universal practice for many years to enclose the ignition distribution systems of aircraft engines in a grounded metallic shield or casing which generally comprises a manifold for a plurality of conductors from which flexible branch conduits for single conductors extend to the individual spark plugs at the cylinders. Most of the failures in shields or harnesses of this character have occurred in the flexible branch conduits which are placed under stress by bending in the initial installation on the engine and which are continuously subjected to severe vibration by wind currents as well as by the unavoidable vibrations of the engine itself. Failure in the shielding conduit generally results in failure of the ignition lead or leads therein and invariably results in radio reception interference. These failures have been prevalent and costly in money, man hours and operating hours, and in most instances have resulted in the loss of personnel and valuable equipment. Accordingly, the problem has had the continuous attention of the best brains in the industry for many years.

It is therefore one of the objects of the present invention to provide a novel radio shielding harness for an ignition system and novel parts thereof wherein failures of the above character are minimized or substantially eliminated.

Another object of the invention is to provide novel means on a flexible metallic conduit having rigid end pieces whereby the conduit is materially fortified against breaking or cracking under the stresses and strains of frequent or continuous bending and vibration.

A further object is to provide a novelly constructed flexible conduit of the radio shielding type having improved physical characteristics.

The above and further objects and novel features of the invention will more fully appear from the following detailed description when the same is read in connection with the accompanying drawings. It is to be expressly understood, however, that the drawings are for the purpose of illustration only and are not intended to define the limits of the invention, reference for this latter purpose being had primarily to the appended claims.

In the drawings, wherein like reference characters refer to like parts throughout the several views,

2

Fig. 1 is an isometric view of one type of ignition shielding harness embodying the present invention;

Fig. 2 is a detail sectional view, with parts broken away, showing the free end of one of the flexible spark plug leads of said harness;

Fig. 3 is a detail view, with parts broken away, showing a different type of terminal on the ignition conductor within a flexible spark plug lead;

Fig. 4 is an enlarged detail view, partly in section and with parts broken away, of one of said flexible leads; and,

Fig. 5 is a side elevation, partly in section and with parts broken away, showing a modified form of flexible conduit.

The shielding harness illustrated in Fig. 1, by way of example, is adapted for use on an inline engine or on an engine of the type having a plurality of banks of radially disposed cylinders with corresponding cylinders of each bank in line. As shown, said harness comprises a rigid metallic manifold tube 10 which is provided with a plurality of spaced outlets 11. Said manifold tube may be of uniform diameter throughout its length but the same is preferably tapered for the purpose of reducing the weight thereof and the space required therefore. Outlets 11 may be in the form of rigid metallic tubes extending at an angle to the longitudinal axis of the manifold tube, the same being soldered or otherwise suitably secured to said manifold tube over openings therein. The enlarged end of rigid tube 10 is preferably mechanically and electrically connected with the casing of a distributor or magneto by means of a flexible manifold section 12, the distributor casing being represented in the drawings by element 14. The latter may be a removable cover for a distributor or magneto casing which may and preferably does have an ignition distributor block or head mounted therein. The ends of flexible section 12 are preferably soldered or otherwise suitably secured to tube 10 and casing member 14 but the same may be detachably connected at either or both ends in any suitable manner known to the art.

Extending from the outlets 11 and from the reduced end of tube 10 are flexible conduits 15 which house the conductors extending to the individual spark plugs (not shown). Although the flexible metallic portions of conduits 15 may be constructed in any of several well known ways to provide good radio shielding as well as good mechanical strength, the specific type shown in the drawings, by way of example, comprises a flexible tube 16 (Fig. 4) made by interlocking the

edges of a spirally wound strip of metal. The flexible tube 16, as shown in Fig. 4, is of the character manufactured by the American Metal Hose Branch of the American Brass Company, but the "Titeflex" and seamless corrugated types of flexible hose may also be used in practicing the invention. In order to enhance the mechanical strength of hose 16, the same is preferably surrounded by one or more, preferably two, layers 17 of braided or woven metallic strips or wires. The ends of each of the flexible metallic conduits 16, 17 extend into rigid metallic ferrules 18, 19 and are suitably secured therein, such as by soldering. Ferrules 18 may be integral with or suitably secured to the outer ends of outlet tubes 11 and ferrules 19 may be integral with or suitably secured to rigid tubular extensions or elbows 20. As best seen in Fig. 2, the ends of metallic conduit 16, 17 engage an internal shoulder in the ferrules 19 and the construction at ferrules 18 may be the same as shown in Fig. 2.

Insulated ignition cables 21 extend from the terminals of the distributor block in casing member 14 into manifold tube 10, 12 and branch out through flexible leads or conduits 16, 17 for conducting high tension current to the spark plugs of the engine. The outer or spark plug ends of each conductor 21 is preferably provided with a plug type connecting terminal which may be of any suitable construction, many of such connectors being well known in the art. In the form shown, the terminal connector for each conductor comprises a flexible insulating tube 22 which extends into elbow 20, a ceramic or similar tip piece 23 and a spring contact 24. The latter may be constructed to operatively cooperate with threads on the outer end of a metallic sleeve 25 secured to the end of the conducting portion of cable 21, such as by soldering or crimping. An internally threaded nut 26 may be provided for electrically and mechanically connecting tube 20 to a shielded spark plug in a manner well understood in the art.

In order to prevent chafing of the insulation on cables 20 and to substantially exclude moisture from the interior of the shielding harness, the space around said cables within the above-described shielding casing is preferably, though not necessarily, filled with a flexible solid insulating compound 27. In one suitable embodiment this compound consists of a mixture of polymerized cashew-nut-shell oil and a drying agent, such as formaldehyde or paraformaldehyde. Other natural or synthetic rubber-like materials may, of course, be used as the filling compound. A spirally cut strip 28 of neoprene or similar material may also be wrapped around each of the cables 20 within conduits 15 to insure adequate spacing of the cables from the inner wall of flexible hose 16.

For the purpose of providing additional insurance against the entry of moisture and other foreign matter into tubes 16, 17 for damping vibrations of said tubes, and for increasing the life of said tubes in various ways, the same are covered in a novel manner. As shown, the covering 29 for each tube 16, 17 consists of a layer of rubber-like material, such as neoprene. Natural rubber or other synthetic elastomers may be successfully used as the covering material. The material of covering 29 preferably fills the spaces between the strands in braided metallic coverings 17 and may penetrate, to some extent, the joints in flexible metal hose 16. With covering 29, it becomes unnecessary to solder or otherwise

pack the joints of hose 16 to prevent the entrance of moisture and the flexibility of the conduits 15 is thereby enhanced. Also, the solid covering 29 prevents the entry of any foreign matter, such as dirt particles, into the woven or braided covering 17, thereby minimizing wear on the latter when it is flexed by bending or vibration.

Although it is not necessary to apply covering 29 throughout the length of each flexible conduit 16, 17, this construction is preferred. The ends of covering 29 extend over and around substantial portions of rigid ferrules 18 and 19. It is this novel feature of the structure shown which substantially prevents breakage of flexible hoses 16, 17 at or near the plane where the same enter said ferrules, i. e., where the breaking of these flexible conduits has been prevalent.

Covering 29 may be applied to hose 16, 17 in any of several ways. For example, when neoprene or similar material is used, the covering may be molded in place by placing strips of unvulcanized neoprene in opposite halves of a two-part mold, by injecting the covering material into the mold, by wrapping the conduit 16, 17 with strips of sheet neoprene or the like before placing it in a mold, or by any other known method, and then vulcanizing or curing the same. During the curing or vulcanizing process, which takes place under pressure during the application of heat, the covering material is pressed into the spaces in the braided covering 17 and into the joints of flexible hose 16. The metallic conduits may also be successively dipped in a bath of compounded neoprene latex and a coagulating bath of acetone, methane, calcium nitrate, or the like. After several such dippings to provide a covering of suitable thickness, the same may be dried and vulcanized. Dipping may also take place in a bath of dispersed compounded sheet neoprene, thereby eliminating the necessity of a coagulating bath. Where the nature of the structure permits, extrusion may be resorted to in applying the covering 29. If desired, some suitable known substance, such as cement, may be used to insure good adherence of the covering material 29 to the outer surface of metallic ferrules 18 and 19. Also, the surface of the ferrules contacted by the covering may be roughened.

In some installations, it may be desirable to make flexible conduits 15 detachable from manifold tube 10. When this is desired, a terminal such as that shown in Fig. 3 may be provided on conduit 15 and conductor 21 for insertion into a socket formed in outlet 11 to which the conduits 15 may be secured in a well-known manner by a nut 30. The sleeve 31 surrounding the terminal end of cable 21 may be similar to tube 22 at the other end of the conduit or the same may be a continuation of the filling compound 27. The socket in the harness manifold for receiving plug 31 may be of any suitable known construction, especially those now in common use on radio shielding harnesses for ignition systems.

If desired, covering 29 may be shaped as shown in Fig. 5 with the radial thickness thereof decreased near the central portion of the conduit. This construction enhances the flexibility of the conduit near the central portion thereof and increases the protection afforded the flexible portion of the conduit near the rigid ferrules at the ends. By thus impeding the flexibility of the conduit near the rigid ferrules substantially all the flexing takes place in the central portion of the conduit where there is less probability of

damage resulting from frequent flexing and vibration.

There is thus provided a novel ignition shielding harness which is more durable under actual operating conditions than similar structures heretofore provided for the same purpose. Said harness comprises a novel flexible shielding conduit which may, per se, be adapted for other purposes and uses. In a simple and inexpensive manner the present invention greatly increases the life and operating efficiency of structures of the type described.

Although only a limited number of embodiments of the invention have been illustrated and described in detail, it is to be expressly understood that the invention is not limited thereto. For example, different types of terminals may be employed on the flexible leads and a ring manifold may be substituted for manifold 10. Various other changes may also be made in the materials suggested as being suitable and in the design and arrangement of parts illustrated without departing from the spirit and scope of the invention as will now be clear to those skilled in the art. For a definition of the limits of the invention, reference is had primarily to the appended claims.

What is claimed is:

1. In apparatus of the class described, a metallic conduit comprising a rigid metallic tubular section, a flexible metallic tubular section with external surface irregularities and having an end portion thereof extending into the end of said rigid section and soldered thereto, said flexible section including a tube which is corrugated throughout its length and a unitary flexible covering of solid insulation surrounding at least a portion of said flexible section outside of and adjacent to said rigid section and extending into overlapping relation with and around the end portion of said rigid section which surrounds the

end of said flexible section, the inner surface of said covering having interlocking engagement with the surface irregularities of the flexible section and sufficient adherence to the outer surface of said rigid section to substantially resist relative movement thereof.

2. Apparatus as defined in claim 1 wherein the flexible corrugated tube comprises a spirally wound strip with interlocking edges.

3. Apparatus as defined in claim 1 including a conductor extending through said conduit, and flexible solid insulation filling the annular space in said conduit around said conductor.

4. Apparatus as defined in claim 1 wherein an outer tube of interwoven metallic strands surrounds said corrugated tube.

5. Apparatus as defined in claim 4 wherein the material of the covering extends between the strands of said outer tube and into the grooves in the surface of said corrugated tube.
